UNITED STATES PATENT OFFICE.

LESLIE L. DARROW AND FREDERICK W. HOESSEL, OF STOCKTON, CALIFORNIA.

LOCKING MEANS FOR DEMOUNTABLE RIMS.

1,407,787.

Specification of Letters Patent. Patented Feb. 28, 1922.

Application filed August 16, 1920. Serial No. 403,763.

To all whom it may concern:

Be it known that we, LESLIE L. DARROW and FREDERICK W. HOESSEL, citizens of the United States, residing at Stockton, in the county of San Joaquin, State of California, have invented certain new and useful Improvements in Locking Means for Demountable Rims; and we do declare the following to be a full, clear, and exact description of the same, reference being had to the accompanying drawings, and to the characters of reference marked thereon, which form a part of this application.

This invention relates to improvements in means for locking demountable rims onto the fixed rim of a wheel, the principal object being to provide a means whereby the two rims may be firmly held to one another without the use of a number of removable clamps or other members, and which will firmly hold the tire holding rim against movement on the wheel, both peripherally and laterally.

In our improved structure, the component parts of the device are permanently mounted on the respective members, so that no pieces can ever jar loose and become lost, and which needs no tools of any kind in positioning the one rim on the other, other than a jack to lift the wheel.

We have also provided a device which is extremely simple to operate, consuming but a few seconds time to either place or remove the demountable rim.

A further object of the invention is to produce a simple and inexpensive device, and yet one which will be exceedingly effective for the purposes for which it is designed.

These objects we accomplish by means of such structure and relative arrangement of parts as will fully appear by a perusal of the following specification and claims.

In the drawings similar characters of reference indicate corresponding parts in the several views.

Fig. 1 is a perspective elevation of a wheel, showing the female locking lugs on the fixed rim.

Fig. 2 is a similar view of a demountable rim, showing the male locking lugs on the same.

Fig. 3 is a cross section through the wheel and demountable rim assembled, showing an eccentric lock for holding the lugs in engagement, when co-operatively placed together.

Fig. 4 is a fragmentary plan of the felly, showing the position of the lockhandle when the lock is engaged. 60

Referring now more particularly to the characters of reference on the drawings, the numeral 1 denotes the felly of the wheel, having the usual fixed rim 2 placed on the same, and provided with the usual flange 3 65 on its inner edge to engage one edge of the demountable rim 4.

Fixed onto the rim 2 in any desired manner are a plurality of L-shaped lugs 5, one leg 5^a of which extends to and merges with the dim-flange 3 at right angles thereto, while the other leg 5^b extends parallel to said flange and has its edge nearest the flange tapered toward the outer end. Thus pockets or recesses 6 are formed, enclosed on 75 three sides by the lugs and rim flange.

The outer faces of these lugs are concentric with the wheel, and fit inside the rim 4, the inner periphery of which is provided with lugs 7 which are exactly the same shape 80 as the pockets 6. It will therefore be seen that if the rim 4 is slid over the rim 2 so that the corresponding lugs clear each other but are in transverse alinement, and the rim 4 is then given a certain amount of radial 85 movement on the rim 2, the lugs 7 will move into the recesses 6, and the two rims cannot have any relative lateral movement.

The end openings of the recesses 6 are in the direction of forward rotation of the 90 wheel, so that the ends 5^a of the lugs 5 bear against the lugs 7 and drive the latter. Fixed to the rim 2 intermediate the lugs 5 are wedge shaped lugs 8, positioned tangential to said rim, and adapted to co-act with 95 similar lugs 8^a on the rim 4. These wedge-lugs are of course so positioned relative to the direction of forward rotation of the wheel that they will climb on one another and wedge together when the wheel is so 100 turned.

These two distinct types of wedge-lugs thus positively hold the demountable rim onto the wheel against both lateral and peripheral movement relative thereto. 105

In order to lock the co-acting lugs in position, and to allow a backing up movement of the wheel without disengagement of the lugs, I provide on the rim 4 a lug 9, and a radial pin 10 in the felly 1 projecting through the rim 2 behind the lug 9 when the rims are in position, this pin having an eccentric head 11 adapted to engage the lug so as to force the lugs on the rim 4 into 110

engagement with the corresponding lugs on the rim 2.

The pin 10 is slidably and turnably mounted in the felly in a sleeve 12 therein, 5 and the felly band has a transversely positioned pocket 13 of a shape to receive the head 11, the latter being forcibly seated therein, after the pin is turned to disengage the head from the lug, by means of a suitably arranged spring 14 on the pin 10. The latter projects through the inner face of the felly and has fixed on that end a spring handle 15 by means of which the pin may be turned.

15 When the eccentric head is disengaged from the lug 9 and is then seated in the pocket 13, the handle then projects transversely of the felly. When the lock is engaged however, the handle moves to be substantially parallel to the felly and to lie on the same, being adapted to be passed over a pin 16 in the felly to prevent a retractive movement of the handle, while the latter is then under tension, being a spring member, 20 as stated. The eccentric head 11 is so shaped and positioned on the pin relative to the handle that when the latter is engaged by the pin 16, the said head will not have turned to its extreme locked position. By means of 25 this construction, therefore, there is always a tendency for the lock to tighten up, rather than to work loose, and this tendency is furthered by the vibration of the wheel as it rotates which soon wedges the lugs into positive and non-movable engagement, and the lock-head follows up the slight forward movement of the outer rim.

The recess 13 for the head 11 is of course necessary, since to remove the rim 4 it must 40 be turned on the other and the lug 9 must pass over the head 11. To manipulate the lock from its seat in the socket, it is only necessary to press the pin 10 inwardly, and while still pressing, turn the handle so that 45 the head 11 will be rotated, when it will at once engage the normal surface of the felly and will then be in the plane of the lug 9.

The rim 4 would preferably have an inwardly projecting flange 17 along its outer 50 edge adapted to seat snugly on the rim 2, so that the space between the two rims is entirely enclosed, the flange 3 being on one side and the said flange 17 on the other. This of course prevents dust and dirt from collecting in said space and entering into the lug recesses when the parts are separated, and gives the wheel an exceedingly neat appearance.

In order to accommodate the valve stem 60 of the tire carried by the rim 4, the rim 2 and felly 1 must of course be provided with a slot 18 of sufficient length to allow for the necessary peripheral movement of the rim 4 on the rim 2, the valve being preferably

positioned directly opposite the lock member 65 to present a balanced appearance.

From the foregoing description, it will be readily seen that we have produced such a device as substantially fulfills the object of the invention as set forth herein. 70

While this specification sets forth in detail the present and preferred construction of the device still in practice such deviations from such detail may be resorted to as do not form a departure from the spirit of the 75 invention as defined by the appended claims.

Having thus described our invention what we claim as new and useful and desire to secure by Letters Patent is:

1. A locking means for demountable rims 80 including interlocking lugs on the felly band and demountable rim, an independent lug on the demountable rim, an eccentric lock-head turnably mounted in the felly and adapted to be turned to engage said lug to 85 hold the coacting lug in positive engagement, a flat spring handle connected to the head on the inner periphery of the felly and extending substantially in a plane parallel to the axis of the heads, and a pin fixed to 90 and projecting inwardly of the felly, the handle being adapted to be snapped past the pin when the former is turned to throw the lock-head into engagement with its lug and to then be under tension, acting to force said 95 head into tighter contact with the lug.

2. A locking means for demountable rims including interlocking lugs on the felly band and demountable rim, said lugs being arranged to be contacted with a relative 100 peripheral movement of the rim and felly band, an independent lug on the felly-band, an eccentric lock-head arranged to be turned to engage said lug to hold the coacting lugs together, and means whereby when the lock-head is turned to be disengaged from its lug, said head will automatically be moved to lie flush with the felly band to allow retractive peripheral movement of the rim. 105

3. A locking means for demountable rims 110 including interlocking lugs on the felly band and demountable rim, said lugs being arranged to be contacted with a relative peripheral movement of the rim and felly band, an independent lug on the felly-band, 115 an eccentric lock-head arranged to be turned to engage said lug to hold the coacting lugs together, a stem fixed to the lock-head and projecting through the felly, the felly band being provided with a recess shaped to receive the head only when the latter is turned to be disengaged from its lug, and a spring about the stem acting to press said head against the band or into said recess. 120

In testimony whereof we affix our signatures.

LESLIE L. DARROW,
FREDERICK W. HOESSEL.
